PERFORATING DIE AND STRIPPING MECH-
ANISM THEREFOR

Lawrence V. Whistler, Kenmore, N. Y., assignor to
 S. B. Whistler & Sons, Inc., Buffalo, N. Y., a
 corporation of New York

Application October 25, 1932, Serial No. 639,447

2 Claims. (Cl. 164—110)

My invention relates to perforating dies and stripping mechanism therefor; also to the manner of securing the same to metal working or other similar presses.

5 One of the objects of my invention is the provision of perforating dies which are adjustably secured to press platens, such as the ram and bed members of a press, and in which new and novel means are provided for so securing them 10 in any position in the areas of said platens.

Another object of my invention is the provision of novel means for retaining the female member of a set of perforating dies on a platen, and to provide new and novel stripping means 15 whereby sheet metal or other material perforated by the dies is stripped from the perforating punch or male member.

Another object of my invention is the provision of new and novel perforating punches and 20 means for retaining them in position, said perforating punches being conveniently removable from the press platen so that others may be substituted therefor.

Another object of the invention is the provision 25 of a stripper element on a perforating punch spring-retained in position by the use of a cushioning element adapted to be compressed, or more fully compressed, under operation of the press.

30 A further object of my invention is the provision of punch elements adapted to be interchangeably secured to a press platen, each punch element having a helical spring surrounding it within a cage having space-apart elements relatively movable, one of said spaced elements being secured to the punch element and the other maintained in position by means of said helical spring and suitable connector elements connecting said spaced-apart elements together.

35 A still further object of my invention is the provision of a stripper device detachably secured to a perforating punch and comprising a cage secured to said punch and extensible and contractile thereon, and a helical spring enclosed 40 within said cage to normally hold the same in extended position and to permit of contracting said cage under pressure applied thereto during perforating action of the press.

45 A still further object of my invention is the provision of punch holders applied to a platen of a press, perforating punches interchangeably securable to the punch holders, and a stripper device removably applied to the perforating punch in use.

50 With the above and other objects in view to

appear hereinafter, my invention consists in the novel features of construction and in the arrangement and combination of parts to be hereinafter described and more particularly pointed out in the subjoined claims.

5 In the drawing:

Fig. 1 is a vertical section through two co-operating platens of a metal-working or other similar press, said platens being equipped with perforating or punching dies and a stripper device representative of my invention.

Fig. 2 is a bottom plan view of a portion of the upper press platen so equipped.

Fig. 3 is a central longitudinal section of my improved stripper device illustrated as a complete unit and detached from the perforating punch.

Fig. 4 is a top plan view of said device.

Fig. 5 is a sectional view of a centering device used temporarily in connection with a templet 20 perforated to assure proper location on the platen of the female member of a pair of perforating dies.

Fig. 6 is a plan view of a portion of the lower platen, showing one of the material gages.

Reference being had to the drawing in detail, the numeral 6 designates the upper platen of a metal-working or other similar press, and 7 the lower platen thereof. In each of these platens, parallel bolt retainer grooves 8 are formed; these 30 being shown of T-formation, but they may be otherwise formed.

Secured to the under side of the upper platen is a punch holder or retainer 9 into which the male member or perforating punch 10 of a pair 35 of perforating dies is secured. This punch holder or retainer is in the form of a bar 11 provided with a longitudinal slot 12 and having at one end a head or enlargement 13 extending downwardly therefrom, said head being axially bored out, as 40 at 14, and having a counterbore or depression 15 at its upper end. The male die members, or more particularly perforating punches adapted to be used in connection with my improved punch holder or retainer, are of like diameter along their upper portions so that they interchangeably fit into the bore 14 of said holder or retainer, while their lower portions may vary in size or diameter, and in shape. In the drawing I have shown a perforating punch whose lower portion is somewhat 50 reduced in diameter and of cylindrical formation so that it will serve to punch a round opening of definite size in a sheet of metal or other material. This lower portion may, however, be reduced twice in diameter from its enlarged upper

55

or securing portion, and may also have its lower or punch end of any desired shape in cross section, depending on the particular shape of the opening to be punched in the material.

- 5 It will be apparent therefore that punches of various shapes and diameters are adapted to be used in connection with the punch holder or retainer 9; and in all instances the punches used in said holder or retainer have their upper or 10 securing portions of a shape and size conforming to the bore 14 of said holder or retainer while their lower portions may be varied and be of different diameters or thicknesses along their length so long as the punch end is shaped to form the desired 15 perforation in the material to be punched. A securing bolt 16 is inserted into one or each or two or more of the retainer grooves 8 formed in the upper platen, they being inserted from the ends of the grooves so that the heads thereof are 20 located in the horizontal or head portions of the Y-shaped grooves while the shank portions of the bolts adjacent said heads are entered into the vertical, or narrow portions of said grooves, the remaining portions of the shanks of said bolt or 25 bolts being passed through the slot 12 in the punch holder or retainer. These bolts have nuts 17 applied thereto which bear against washers 18 placed against the punch holder or retainer. These punch holders or retainers may be adjusted 30 lengthwise, or rotated on one of said bolts while sliding the other bolt in its retainer groove and varying the position thereof in the slot of the punch holder; or, when a single bolt is used, the punch holder may be rotated on the bolt so as to 35 assume any angular position desired. In this manner a punch held within said punch holder or retainer may be positioned at any desired point within the area of the platen. In some instances the bar 11 is positioned at a right angle to the 40 T-shaped grooves in the platen, in other instances parallel thereto, and it may be positioned at any desired angle with respect to said T-shaped grooves.

Positioned within the counterbore or depression 45 15 of the punch holder or retainer is a hardened wearing plate 19, it being backed-up by the platen and being adapted to have the upper end of the perforating punch 10 bear thereagainst.

Each perforating punch is notched, as at 20, the 50 notch being of substantially V-formation and extending across the peripheral surface of the upper or securing portion of the punch. Both walls of each notch are therefore obliquely disposed and into the head or enlargement 13 of the punch 55 holder or retainer a securing screw 21 is threaded, a tapped screw opening being provided for said securing screw and extending from the outer face of said head or enlargement inwardly obliquely to the bore 14 therein, the axis of said 60 tapped screw opening being preferably parallel with one of the walls of the V-shaped notch in the perforating punch and at right angles to the other wall thereof.

The securing screw 21 has its inner end portion 65 reduced in diameter, as at 22, and this reduced portion is smooth surfaced or unthreaded and adapted to be entered into the V-shaped notch of the punch so as to bear against the upper or contact wall portion of said notch. The 70 perforating punch is thus securely held within the punch holder or retainer and can be quickly and easily removed therefrom when it is desired to replace it with another; it being simply necessary to unthread the screw 21 so as to cause the 75 inner smooth surfaced end portion of said screw

to recede fully into the tapped screw opening in the head of the punch holder or retainer.

I preferably continue the diameter of the upper or securing portion of the punch downwardly a distance below the head or enlargement 13 of the punch holder or retainer and secure thereto a stripper device, designated as a whole by the numeral 23. This device is in the form of a cage and comprises an upper member or header 24, a lower member or header 25, a circular series 10 of guides 26 on which said members are relatively movable towards and away from the other, and a helical spring or other cushioning element 27 interposed between said upper and lower members or headers and surrounded by said circular 15 series of guides. The upper member or header 24, which may also be referred to as a securing member or header, has a radially-disposed tapped opening formed therein into which a securing screw 28 is threaded, which firmly bears against 20 the perforating punch 10 axially entered in the upper member or header and securely fastens said member or header to the punch. The said header is provided on its under side with a central downwardly-opening depression or pocket 29, 25 and it is peripherally notched, as at 30, the notches extending from the upper face of said header downwardly to a plane within a short distance of the lower face thereof so as to provide stop lugs 31, for a purpose to presently appear, 30 said stop lugs forming the lower walls of said notches. These stop lugs are provided with smooth-surfaced bolt holes 32 and axially aligned therewith are bolt holes 33 which are formed in the lower member or header 25 of the stripper 35 device. The guides 26 are in the form of rods, and more particularly considered, screw bolts having their heads normally entered in the notches 30 and bearing against the upper faces of the stop lugs 31 in the upper member or header, 40 while their lower extremities are screw-threaded and entered into the tapped bolt holes 33 in the lower member or header 25.

The helical spring 27 is interposed between the two members or headers, as stated, and surrounds 45 the perforating punch, the upper end of this spring being entered into the depression or pocket 29 in the upper member or header and it has its lower end bearing against the upper face of the lower member or header 25.

The lower member or header 25 has an axial opening 34 therein into which, or through which, the lower or punch end of the perforating punch is passed; the arrangement being preferably 55 such that the punch end of said punch terminates within said opening. Wobbling of the lower member or header 25 is therefore avoided, and assurance of movement of said header in a perfectly vertical direction assured.

The helical spring is normally under slight 60 compression so as to exert pressure against the lower member or header 25 of the stripper device and cause the heads of the guides or guide bolts 36 to bear against the lugs 31 of the upper member or header 24.

I preferably secure the stripper device to the punch in such position that one of the notches 30 of the upper member or header 24 is in line with the securing screw 21 so that this screw is easily accessible when it is desired to change 70 the perforating punch; this arrangement being of particular advantage in such instances where the upper member or header 24 of the stripper device approximates that of or is of greater diameter than the head or enlargement 13 of the punch 75

holder or retainer. For the purpose of increasing the accessibility of a tool to the securing screw 21, I find it of advantage to notch or cut away the head or enlargement 13 of the punch holder 5 or retainer, as at 35, directly over a notch 20 in the upper member or head 24 of the stripper device, said notch or cut-away portion facing downwardly and outwardly.

A die retainer 36 is applied to the lower platen 7 of the press and this comprises a bar 37 provided with a longitudinal slot 38 and having at one end an upstanding head 39, cupped at its upper end to receive a female die 40 provided with an axial opening 41, which is preferably downwardly flared and the upper end of which is of a diameter or size and also of a shape to conform to the lower effective punch end of the perforating punch 10. This upstanding head has an opening 42 extending from the female die 40 downwardly and outwardly to the side of the head 39 so that material punched out of a sheet of metal or the like, designated by the numeral 43 and lying upon the female die, may be directed through said die and through said opening and be deposited on the lower platen, from which it may be removed, as and when desired.

Securing bolts 44 are entered into the T-shaped retainer grooves of the lower platen in the manner in which the securing bolts 16 are entered into the bolt-retainer grooves of the upper platen, and these bolts are passed through the slot 38 of the die retainer. Nuts and washers forming part of said bolts serve to securely fasten the die retainer to the lower platen in the same manner as the nuts and washers 17 and 18, respectively, employed to secure the punch holder or retainer to the upper platen.

The sheet of metal or other material is positioned in contact with one or more gages 45, one of which only is shown fastened to the lower platen and extends upwardly therefrom; but, if desired, these may be fastened to the upper platen and extend downwardly therefrom. These gages are spaced apart along at least one dimension of a platen and each comprises an angular structure having a horizontal arm 46, slotted as at 47, and a vertical arm 48, which is an upstanding arm in the application illustrated.

Securing bolts 49 are entered in the bolt-retaining grooves 8 of the lower platen in the same manner as the securing bolts 16 and 44, and these are passed through the slots in the horizontal arms 46 of the gages, washers and nuts forming part of such bolts being employed to tighten the gages to the platen.

By trending the T-shaped retainer grooves in one direction and in parallel relation, the perforating dies may be secured to the platens in co-axial alinement and at any desired points in the areas of said platens; the position of these dies depending on the exact location the perforations are to be formed in the sheet metal or other material to be punched or perforated.

Prior to commencing the punching or perforating operation it is necessary to ascertain the exact points of location of the die members on the platens, and this is accomplished by positioning the gages on one or the other of the platens and placing a templet having small position-locating or centering openings therein against the gages. Preparatory thereto, however, the die retainer 36 is loosely positioned upon the lower platen, it having been provided with a centering plug 50 shown in Fig. 5. This plug is fitted into the upstanding head 39 of the die

retainer and extending axially therefrom in an upward direction is a centering point 51 which is adapted to fit the small position-locating or centering opening of the templet. The die retainer is then moved into such position on the platen that this centering point will be positioned in the opening of the templet while the latter is held against the gages, after which the bolts 44 of the die retainer are tightened. The templet is then removed from the machine, the centering plug from the die retainer, and the proper female die member inserted in the die retainer.

The male die or punch element, hereinafter referred to as the perforating punch, is then positioned on the upper platen so that it will be centered with respect to the female die member, and after tightening the punch holder or retainer to which the perforating punch is secured, the press is ready for operation.

The sheet metal or other material to be operated upon is inserted into the press to assume the position shown in Fig. 1, after which the upper platen is lowered to cause the stripper proper or lower member or header 25 to engage the upper surface of the material. This causes the spring 27 of the stripper device to be compressed and the guide bolts 26 to travel upwardly in the openings 32 of the upper member or header 24 of the stripper device, the heads of said guide bolts 30 moving away from the stop lugs 31 formed on said upper member or header. Simultaneously therewith the perforating punch 10 is lowered and pressed through the metal or other material so as to enter the female die member 40, with the metal punched from the sheet in advance thereof. After the punching or perforating operation, the upper platen is elevated, causing the perforating punch to be withdrawn from the female die member and from the opening which it formed in the sheet metal or other material, and as said punch becomes released from the sheet metal the stripper element 25 remains momentarily in contact with the metal under the expansive force of the spring 27 until this force causes the guide bolts 26 to be moved to normal position with their heads in contact with the stop lugs 31, after which the continued upward movement of the upper platen of the press will cause said stripper element to be moved out of engagement with the sheet metal or other material so that this material, properly operated upon, can be freely withdrawn from the machine.

The stripper device, comprising the two headers 24 and 25, the helical spring 27, and the guide bolts 26, therefore hold the sheet metal or other material being punched or perforated in contact with the female die member, until after the punch is fully withdrawn from said material.

For the purpose of clearness I distinguish between the stripper device as an entirety and the stripper or stripper element 25 in that I consider the element brought into direct and actual contact with the material operated upon to be the stripper proper, while this element associated with other parts form the complete stripper device, which is removable as a unit from the perforating punch.

When a hole larger or smaller is required than that which the perforating punch in the press will make, or a hole which is of different formation, the perforating punch is removed from the punch holder or retainer 9 with the stripper device attached thereto; or if desired, the stripper device may be removed from the perforating

punch before removing the punch from its holder or retainer. A new perforating punch containing a smaller, larger, or different form of punch end, as the case may be, may then replace the punch removed, either with or without a stripper device attached thereto; but, if desired, certain elements of the same stripper device may be employed, as it will only be necessary that the lower member or header 25 has an axial opening 10 conforming to that of the lower or punch end of the substituted perforating punch. Replacement of the lower member or element of the stripper device can be easily accomplished by unthreading the guide bolts 26 from the tapped bolt holes 33 in the lower member or header of the device and then axially positioning another having a different axial opening and threading the guide bolts 26 into the tapped openings thereof.

While in the drawing I have shown a single 20 set or pair of die members, it is to be understood that a plurality of such sets are oftentimes used, and that therefore the drawing is merely representative of my invention and of the use thereof.

It will be apparent that in my improved stripper 25 device, the spring 27 is confined within an open-work housing or cage, and that in the event of the spring becoming broken, it will not cause damage to the dies or the material worked upon, since the broken portions of the spring will be 30 wholly confined within the housing or cage, and retain its position around the perforating punch, even though ineffective in maintaining the stripper proper under spring pressure.

Having thus described my invention, what I 35 claim is:

1. The combination of a punch retainer se-

cured to a platen and having a cut-away portion 5 facing downwardly and outwardly, a punch having one end removably fitted in said retainer and having a peripheral notch therein presenting faces at an angle to each other, said faces being both disposed obliquely to the axis of said punch, a securing screw adjustable within said punch retainer and having its inner end entered in said peripheral notch and its outer end accessible by way of said cut-away portion, and a stripper de- 10 vice surrounding the lower portion of said punch and comprising an upper header secured to said punch directly beneath said punch retainer and having a peripheral notch in vertical alignment with the cut-away portion of said punch retainer, 15 guide rods slidably fitted in said upper header and having enlargements normally bearing against said header, a lower header into which the lower ends of said guide rods are secured and having an axial opening into which the lower portion of said punch is slidably fitted, and a helical spring interposed between said headers around said punch.

2. A punch retainer having a cut-away portion 25 facing downwardly and outwardly, a punch having one end fitted in said retainer and having a peripheral notch at said end, a securing screw threaded into said punch retainer and having its inner end entered within said peripheral notch and its outer end accessible by way of said cut-away portion, and a stripper device applied to the projecting portion of said punch and having a peripheral notch in vertical alignment with the cut-away portion of said punch retainer to permit access to said securing screw. 30

LAWRENCE V. WHISTLER. 35
